UNITED STATES PATENT OFFICE

2,561,821

FIXTURE

Roy S. Sanford, Woodbury, Conn., assignor to The
Autoyre Company, Incorporated, Oakville,
Conn., a corporation of Connecticut

Application May 24, 1947, Serial No. 750,347

3 Claims. (Cl. 45—28)

1

The present invention relates to a wall fixture and has special reference to such a fixture comprising a bracket for attachment to a wall or similar support and a multiple-part tray or dish detachably supported thereby.

More particularly this invention relates to a multiple-part dish comprising upper and lower tray members and a bracket having opposed arms for resiliently and detachably supporting said dish and maintaining the parts or members thereof in proper combined or assembled position.

The multiple-part tray or dish contemplated herein such, for example, as a soap dish, may comprise a lower imperforate tray for catching any soapy water that drains from the soap and an upper perforate tray nested therein and spaced a distance thereabove forming a space or chamber between the two. Consequently, when the soap is placed on the upper tray, the soapy water drains through the perforations into the chamber below where it collects. The upper and lower tray members of the dish are readily separable to provide easy access for cleaning. When the parts are assembled, the dish may be quickly inserted between the arms of the bracket. These arms support the dish and also serve to prevent separation of the upper and lower tray members while engaged thereby.

Moreover, the screws or similar securing means for mounting the bracket on the wall or other support are so positioned that they will be completely concealed from view when the dish is supported by the bracket.

An object of the present invention is to provide a fixture having a multiple-part dish or tray detachably supported by a bracket which, while supporting the dish or tray, maintains the parts thereof in proper assembled position and prevents unintended separation thereof.

A further object is to provide such a fixture in which the bracket is provided with arms for resiliently grasping the dish or tray.

A still further object is to provide a fixture as referred to above in which the dish members are readily separable when not associated with the supporting bracket.

Another object is to provide such a fixture, substantially all the parts of which may be readily formed by relatively simple stamping operations at a minimum of cost.

Still another object is to provide a fixture of the type above referred to in which the means for securing it to a wall or other support is concealed from view when the fixture is assembled.

Further objects and advantages will be appar-

2

ent from the following description and claims when considered with the accompanying drawings in which:

Figure 1 is a top plan view of a fixture embodying the present invention;

Fig. 2 is a side elevational view thereof;

Fig. 3 is a central, vertical cross-sectional view taken along the lines 3—3 of Fig. 1;

Fig. 4 is an end elevational view;

Fig. 5 is a central, vertical cross-sectional view taken along the line 5—5 of Fig. 1; and

Fig. 6 is a perspective view of the dish-supporting structure of the bracket.

Referring more particularly to the drawings, there is shown a fixture embodying the present invention designed particularly for use as a soap dish or tray comprising a multiple-part soap dish and the supporting bracket therefor.

The bracket may comprise a vertical portion 10, preferably of sufficient size to form a splash guard for being secured to a wall or other supporting structure.

Secured to the vertical portion 10 by welding, soldering, or other suitable means is a dish-supporting structure 11 comprising opposed arms 12 and 13, preferably channel-shaped in cross section, and a member 14 connecting the inner ends thereof, also preferably channel-shaped in cross section. Securing means, such as screws 15, which project through the vertical web at the rear of the connecting member 14, serve to mount the bracket on the wall 16 or other supporting structure.

When the bracket supports a substantially hexagonal dish, such as shown in Fig. 1, the arms are outwardly bowed with the terminal portions 17 and 18 thereof at a slight angle to the inner portions of the arms, so that the arms will fit the opposite ends of the dish. Obviously, when dishes of other shapes are used the arms will be correspondingly shaped to securely hold the dish employed therewith.

The metal portions 19 which join the connecting member 14 with the arms 12 and 13 provide sufficient resiliency to permit the arms to be spread apart upon insertion and removal of the dish therefrom, and when the dish is in position will prevent unintended removal thereof. Other suitable arrangements for providing resiliently mounted arms may be employed.

Each of the arms 12 and 13 is also provided with upper and lower dish-engaging flanges 20 and 21 respectively, and the connecting member 14 may also be provided with similar dish-engaging flanges 22 and 23.

The multiple-part dish illustrated comprises

a lower imperforate tray 24 having an upwardly extending peripheral flange 25, and an upper tray 26 projecting within the lower tray 24 and having a downwardly extending flange 27 adapted to overlie the flange 25 of the lower tray. The flanges 25 and 27 are shaped to provide an outwardly extending peripheral bead 28, the vertical width of which is such as to permit it to fit between the top and bottom flanges of the arms 12 and 13 and the connecting member 14. The flanges 25 and 27 also serve to properly space the upper tray 26 from the lower tray 24. Upwardly extending transverse embossments 29 are provided to support the soap above the bottom of the inner tray 26. Perforations 30, formed in the bottom of the tray 26 adjacent the embossments 29, permit soapy water to escape there-through and collect in the bottom tray 24.

With the above construction, the upper and lower trays 26 and 24, respectively, may be readily and quickly separated for cleaning or any other purpose when not engaging the bracket. However, when the trays in assembled relation are inserted between the channel-shaped arms 12 and 13, the flanges 20 and 21 thereof will engage the upper and lower surfaces of the bead 28, as shown in Fig. 3, thereby preventing separation of the trays.

The portion of the bead 28 at the rear of the dish also preferably engages the upper and the lower flanges of the connecting member 14, as illustrated in Fig. 5.

The dish, therefore, may be easily and quickly inserted between the arms 12 and 13 or removed therefrom and, when positioned between the arms, separation of the upper and lower trays is prevented. Moreover, when the dish is supported by the bracket, the rear side thereof conceals the screws 15 from view presenting a very pleasing and expensive appearing fixture.

The present invention has been described in connection with the soap dish illustrated. However, it is capable of many additional uses, and the upper and lower trays of the dish may be substantially flat or of any other shape desired, depending upon the use for which the dish is intended.

While I have shown a particular embodiment of my invention it will be understood, of course, that I do not wish to be limited thereto since many modifications may be made and I, therefore, contemplate by the appended claims to cover any such modifications as fall within the true spirit and scope of my invention.

Having thus described my invention what I claim and desire to secure by Letters Patent, is:

1. In combination, a multiple-part dish having a lower imperforate tray member and a readily separable upper perforate tray member, said members being normally arranged in nesting relationship, and means for preventing separation of said tray members and for supporting said dish, comprising a wall-engaging bracket provided with a pair of opposed outwardly-extending arms having a part connecting said arms, said arms and part being channel-shaped in

cross section for receiving and engaging peripheral portions of said tray members, and said part having a rear wall, and securing means projecting through the rear wall of said part for securing the bracket to a support, said securing means being concealed by said dish when the latter is supported by said bracket.

2. A fixture comprising a wall-engaging bracket having a central connecting member and an outwardly extending arm at each end thereof, a multiple-part dish comprising a lower imperforate tray member and an upper readily-separable perforate tray member, each of said tray members having a peripheral flange projecting toward the other to form a peripheral beaded portion intermediate the outer faces of said trays when said trays are nested together, the portion of said bracket adjacent the juncture of said connecting member and said arms being resilient and said connecting member and arms at each side of said resilient portions being channel shaped in cross section to receive said peripheral beaded portion therein and prevent separation of said tray members while supporting said dish.

3. A fixture comprising a wall-engaging bracket having a central connecting member and an outwardly extending arm at each end thereof, a multiple-part dish comprising a lower imperforate tray member and an upper readily-separable perforate tray member, each of said tray members having a peripheral flange projecting toward the other and arranged to form a peripheral beaded portion intermediate the outer faces of said trays when said trays are nested together, the portion of said bracket adjacent the juncture of said connecting member and said arms being resilient and said connecting member and arms at each side of said resilient portions being channel-shaped in cross section to receive said peripheral beaded portion therein and prevent separation of said tray members while supporting said dish, said connecting member having the channel therein of greater depth than the width of the bead to be received in said channel and being provided with a rear wall, and securing means projecting through the rear wall of said connecting member for securing the bracket to a support.
